(57) **CLAIM**

The ornamental design for a perforated information card for coreless rolls of material, as shown and described.

DESCRIPTION

FIG. 1 is a front elevation view of a perforated information card for coreless rolls of material showing the claimed design, wherein the dotted broken lines of the drawing represent perforations;

FIG. 2 is a top elevation view thereof;

FIG. 3 is a bottom elevation view thereof;

FIG. 4 is a side elevation view thereof;

FIG. 5 is a rear elevation view thereof, wherein the dotted broken lines of the drawing represent perforations;

FIG. 6 is a perspective view of the perforated information card of FIG. 1 shown in use, the dashed broken lines represent the environment in which the design resides and forms no part of the claim, and the dotted broken lines represent perforations; and,

FIG. 7 is a perspective view of the perforated information card of FIG. 1 shown in use, wherein the dashed broken lines represent the environment in which the design resides and forms no part of the claim, and the dotted broken lines represent perforations.

The dotted broken lines shown in FIGS. 1 and 5-7 of the drawing represent perforations. The dashed broken lines of the drawing are for illustrative purposes only and form no part of the claimed design.

1 Claim, 3 Drawing Sheets
